UNITED STATES PATENT OFFICE.

RAYMOND D. SMITH, OF YONKERS, NEW YORK, ASSIGNOR, BY MESNE ASSIGNMENTS, TO TREMONT PRODUCTS CORPORATION, OF BOSTON, MASSACHUSETTS, A CORPORATION OF MASSACHUSETTS.

INCLOSED EXTERNALLY-OPERATED TIME SWITCH.

Application filed May 8, 1918, Serial No. 233,350. Renewed March 22, 1923.

To all whom it may concern:

Be it known that I, RAYMOND D. SMITH, a citizen of the United States, residing at Yonkers, in the county of Westchester and State of New York, have invented new and useful Improvements in Inclosed Externally-Operated Time Switches, of which the following is a specification.

This invention relates in general to ¹⁰ closed electric switches that incorporate mechanism for effecting automatic actuation of the same, and specifically pertains to a certain type of time switch wherein ordinarily the switch alone is adapted to be operated through conventional control means by direct hand manipulation; but wherein switch-operating mechanism, as and when desired, may readily be established under tension tending to effect automatic actuation ¹⁵ of the switch,—a normally idle timer being present that may be rendered active for pre-determining the elapse of time before such actuation occurs. An example of this type ²⁰ of time switch is disclosed in my co-pending application, Serial No. 207,303, filed Dec. 15, 1917.

My present invention has as its broad object to provide an improved form of time switch that is more simple as to mechanism ³⁰ and more convenient for the layman to operate than time switches as heretofore known; and particularly to provide an improved form of safety housing with simple exterior control means for operating the switch and the timer,—the combined switch, timer and inclosing structures embodying co-operative features of construction and function that enable my improved time switch satisfactorily to meet the many and ³⁵ stringent commercial requirements imposed upon inclosed, hand-operated, electric switches of considerable load-governing capacity.

Such requirements are, in part, for quick ⁴⁵ contact-separating movement at each circuit-breaking action of the switch to prevent arcing; and for special provision regarding ease of operation by the layman, involving the necessity for prominent and unmistak-

able indication as to whether the closure-concealed switch is "on" or "off", the provision of safety interlocking means between the switch and the movable casing cover governing access thereto for automatically guarding the operator from shock through ⁵⁰ accidental contact with electrically alive parts, as well as provision for permanently locking the closure of the switch, of the fuses, or of both, to prevent tampering therewith by unauthorized persons. ⁶⁰

My present invention while providing for requirements such as these may also be regarded as an improvement of the time-switch disclosed in my co-pending application referred to above, and thus viewed has ⁶⁵ for a specific object to simplify and render more convenient to manipulate the general type of operating mechanism characterizing that form of time-switch;—one means to this end, in the present disclosure, being the ⁷⁰ elimination of a certain hand-actuated, latch-tripping device heretofore employed in operative association with the usual switch control handle and necessitating, before the present improvement, a special mode of manipulation for operating the switch. ⁷⁵

Another specific object of my invention is to provide a novel and effective spring-buffer construction for absorbing the hammer-blow of the movable, circuit-governing switch ⁸⁰ member, which member, in the present instance, is acted upon by a spring to cause, in an improved manner, the advantageous, quick-contact breaking movement thereof, both when said member is operated directly ⁸⁵ by hand and when operated automatically under control of the timer. In a preferred form I arrange this buffer, as will herein-after be fully described, so that the yielding movement thereof (when the buffer is ⁹⁰ subjected to the thrust of the spring-actuated member) operates automatically to perform the latch-tripping function that requires, in the time-switch of my said co-pending application, special manipulation ⁹⁵ of the said latch-tripping device herein eliminated.

The compactness resulting from this and

other simplification, enables me conveniently to house the entire switch and timer structure, with or without fuses, in a box or casing of substantially regular outline and attractive appearance,—such casing being preferably free from cuts, slots and the like, as are sometimes employed for the protrusion of operating handles in inclosed switch construction. This casing, however, has suitable openings arranged preferably to give separate access to the timer enclosure and to the switch enclosure (which latter commonly contains fuse blocks). The opening to the timer chamber may be closed by a permanent cover attached by screws or other suitable means; but the opening to the switch chamber, particularly when fuse blocks are located therein, must be readily accessible.

Concerning the last-mentioned opening, it is a further object of the present invention to provide a movable, and preferably a hinged, cover therefor, mutually co-operating with the circuit-governing switch member before mentioned (or some part connected to move in unison therewith) so that this movable cover is positively locked in a position to prevent access to the switch or fuse chamber except when the switch is in its fully "off" position; and further so that the switch is positively locked against movement away from its said fully "off" position except when said cover is in its said position for preventing access to the switch or fuse chamber.

Also contributing co-operatively to the stated broad object of the invention, my improvement aims to provide an effective means of prominent and unmistakable indication, conspicuous to the operator's view, for informing him at all times whether the concealed switch is "on" or "off". Such means of indication are particularly necessary in the specific embodiment of my invention herein disclosed, for in such embodiment, as will later appear, the exterior switch control handle does not necessarily hold a fixed position relative to the inclosed, movable switch member which it actuates, and, therefore, is incapable of serving as a true indicator of the position of the switch.

In a further developed form, I herein show how this means of indication may advantageously be extended to embrace a system of individually registering signs; wherein means are provided not only for informing the operator as to the true position of the switch, but in a separate casing window there is caused successively to appear as a result of each operative movement of the circuit-governing switch member alone, of the exterior control handle alone, or of both these parts in unison, a differently worded sign clearly directing the operator how next

to manipulate the control agencies (either of the switch or of the timer) for further operating the time switch.

As will be seen from the following detailed description of the specific embodiment of my invention illustrated in the principal figures of the drawings, all of the improved provisions constituting main features of the present invention as outlined above are structurally co-related and co-operative in the production of a common result, namely the provision of a simplified, inclosed time-switch, designed for direct, exterior hand-operation of the switch (as in the case of an ordinary, non-automatic, inclosed knife-switch), which at once is economical to produce, well adapted to commercial requirements and particularly convenient and suitable for non-experts to use under practical service conditions. In addition to the main features of the invention above referred to, the hereinafter following description will disclose other novel and advantageous details, that contribute co-operatively to the broad object of the invention first stated.

Illustrative embodiment, demonstrating how the principles of my invention may be applied, and their advantages derived in practice, appear in the accompanying drawings that form a part of this specification wherein:

Fig. 1 is a front view of an improved switch and timer structure that embodies the co-operative features of my invention and shows the switch as tensioned for automatic action under control of the timer,—the front cover for the timer chamber being partially broken away to show the interior parts, and the hinged hood that incloses the switch therebelow partially appearing in open position and sectioned on the plane 1—1 in Fig. 8, together with certain safety locking parts, co-operating therewith. The exterior locking parts are shown positioned as in said Fig. 8; which, however, (as is indicated by a break in the connecting shaft) is a false position relative to the interior switch-operating mechanism as the latter is positioned in Fig. 1.

Fig. 2 is a complete sectional view taken mainly on the vertically continuous planes 2—2—2, etc., in Fig. 1,—but with certain of the timer operating parts, locally and centrally sectioned better to show their construction,—the switch-covering hood here appearing as swung up to its closed position.

Fig. 3 is a fragmentary front view showing the upper front cover for the timer chamber, and certain indicating mechanism partly carried thereby.

Fig. 4 is a view looking in the direction of the arrows from the plane 4—4 in Fig. 2, showing certain details partially concealed in Fig. 1.

Fig. 5 is a sectional view taken on the

central vertical plane 5—5 in Fig. 1, showing the construction and relation of certain detent parts through which automatic movement of the switch is controlled by the timer.

Fig. 6 is a view in right elevation showing the lower part of my improved time switch with the switch control arm that is exterior of the switch chamber positioned correspondingly to the interior mechanism 10 as the latter appears in Fig. 2.

Fig. 7 is a view in left elevation of the lower portion of my improved time switch showing the automatically operative parts for effecting safety interlocking action between the switch and its covering hood,—all 15 of these parts here appearing in their true relation to the interior switch-operating mechanism as the latter is positioned in Figs. 1, 2 and 7, and the said hood being closed, 20 but partially cut away, together with the casing box, to show certain of the interior parts.

Fig. 8 shows the position assumed by the parts in Fig. 7 when the switch is in its 25 “off” position and the switch-covering hood is opened.

Fig. 9 is a partial sectional view looking downwardly from the horizontally continuous planes 9—9—9 in Fig. 1, showing the 30 same switch-and-hood, interlocking parts in plan view, together with the sheet metal brackets that support the switch operating mechanism,—all movable parts occupying the same position as in Fig. 7.

Fig. 10 shows a further developed modification of the type of indicating mechanism appearing in Fig. 3, together with certain switch-operating parts as modified to co-operate therewith.

Fig. 11 is a sectional view taken on the vertical planes 11—11 in Fig. 10. As certain sheet metal sign carriers appearing in this figure are, in actual dimension, very thin and ride substantially in surface contact, one behind another, they have been indicated for clearness in this figure merely by single lines.

Figs. 12, 13, 14, and 15, however, which are fragmentary sections taken respectively 50 on planes indicated by corresponding numerals in Fig. 10, by exaggerating the dimensions of thickness and spacing of these sign carriers, clearly show the co-planar relation of certain ears formed to overlap at different points on certain of the carriers 55 for co-operating in the movement of others of the carriers.

Fig. 16 is a view looking at the right of the switch operating parts of Fig. 10;—these 60 parts, in Fig. 16, being shown on the sheet of drawings as positioned in true operative relation to the indicating parts that appear in Fig. 11, when the switch is in its “off” position.

Fig. 17 shows the indicator parts of Fig.

10 as positioned when the switch is normally established in its “on” position.

Fig. 18 is a view looking at the right of Fig. 17.

Fig. 19 shows a change in sign-carrier position brought about by tensioning the switch for timer-controlled operation.

Figs. 20 and 21 show, respectively in plan and in front elevation, a possible provision for fuses that necessitates a lengthening of the switch closure in its bottom portion.

Fig. 22 shows an advantageous modification in the hood and switch interlocking safety construction through which the same principles of interlocking action characterizing the cams of Fig. 7 may be preserved when these cams are spaced further apart (as to accommodate the lengthening of the casing indicated in Figs. 20 and 21). In Fig. 22, the switch covering hood is permanently locked closed and the switch is in “off” position but entirely free to be operated.

Fig. 23 is a view taken in section on the vertically continuous planes 23, 23, etc., in Fig. 22.

Fig. 24 shows the parts of Fig. 22 as they are positioned when the switch is permanently locked in its “off” position and when the casing is open but entirely free for swinging movement to open or close.

Fig. 25 shows how the parts in Figs. 22 and 24 may be availed of to lock the switch in its “off” position and at the same time to lock the switch-covering hood in its closed 100 position,—permanently and by a single padlock.

Fig. 26 is a perspective view of the complete switch-operating and timer mechanism with the cover parts removed and with 105 the panel fins omitted so as to better show details of the mechanical structure.

Fig. 27 is a detached view in perspective showing the construction of a detent part.

Fig. 28 is a perspective view of the sign 110 carrier mechanism and certain parts of the switch co-operating therewith.

Fig. 29 is a side view similar to Fig. 2 showing an embodiment of the addition of certain spring and detent parts to make the 115 switch perform a double automatic action at respectively different times under the control of the timer.

Fig. 30 is a front view of the timer and detent parts shown in Fig. 29 and is taken 120 on the vertical plane 30—30 in that figure.

The same reference numeral, when appearing in more than one of the above described figures, identifies different views of the same element.

The general structure.

These details of construction that will first be described are illustrated principally in Figures 1 to 9, inclusive, of the draw- 130

ings. In these figures, the main parts of my complete switch and timer structure (disregarding, for the present, the housing in which they are inclosed) are shown as 5 connected by, and mounted upon, a common support plate 10 that extends nearly throughout the length and breadth of the complete structure at the back thereof. On the upper portion of this plate is rigidly 10 mounted (in a manner to be readily removable), by screws 11 and spacing washers 12, the rear frame plate 13 of a simple balance-wheel, escapement movement that comprises part of the time later to be more fully 15 described, and that compositely is designated by the numeral 14; while to the lower portion of this support plate, is secured a switch panel 16 preferably moulded from insulating material, and formed with two 20 forwardly protruding, parallelly disposed, fan-shaped fins 17, that are shown as braced for strength by laterally sloping ribs, 18, 19, etc.

The switch.

25 On the switch panel 16 are mounted hinge clips 19, contact clips 21 and corresponding binding post screws 22 for lead wires 23, the electric circuit through which is to be 30 made and broken by swinging movement of two conductive blades 24, 24,—of ordinary knife-switch construction,—the said blades being bridged at their tops, as usual, by a connecting bar 26 of insulating material 35 which is thus carried in a position to span the channel space between the panel fins 17, 17.

Within this channel space and effectively 40 separated by the panel fins 17, 17 from all possible interference with, or by, the electrically alive parts, is located a rugged switch actuating mechanism composed of few and simple punched metal parts and having operative connection as hereinafter 45 to be described with the switch connecting bar 26 of the switch blades.

The frame-work.

The support frame for this switch actuating 50 mechanism comprises, in the form shown, two sheet-metal brackets 27, 27 that are each bent to a rectangular U-shape, the two arm portions thereof extending forwardly from behind the switch panel 16 and one arm 28 of each bracket lying respectively adjacent to the extreme side edges of said panel while the other two bracket arms 29, 29 protrude adjacently through a common central cut-away in the bottom portion 55 of the panel and in the support plate 10. At their place of attachment to the back of the panel, these brackets, as best shown in Figs. 2 and 9, are rigidly and independently riveted or screwed to the support plate 10, which latter overlaps the

60 bracket 27 at the rear surface of the switch panel,—this arrangement providing a cheaply produced, but a rugged, support-frame structure that entirely relieves the relatively frail, moulded, switch panel 16 of all 70 mechanical strain.

The actuating mechanism.

As best shown in Figs. 1, 4 and 9, the 75 two centrally adjacent arms 29, 29 of brackets 27 are parallelly disposed and fall within the channel space between panel fins 17,—there being a small space between said arms to accommodate a switch actuator lever 31 mounted to swing on the bracket-carried pivot pin 32. This actuator lever, as shown, is blanked from flat sheet metal without bends, but as Fig. 2 shows, is cut to such shape that its upper portion is parallelly disposed in offset relation to its pivoted 80 end portion,—this shape forming two obtuse angle, elbow portions within the length of the lever. On both sides of that elbow portion of lever 31 which is nearest the pivot pin 32, said lever carries a fixed pivot stud 85 90 95 100 105 110 115 120 125 130 135 140 145 150 155 160 165 170 175 180 actuator lever and the switch blades, though separately pivoted, are pivoted in substantially concentric relation, it will be understood that normally the said lever, its carried buffer structure, and the blades are all adapted to swing in unison, thus being abuttingly positioned.

For manually swinging the actuator lever 31, any suitable handle provision may be made,—the present disclosure for sake of illustration, showing a bail crank 47 pivoted at 48, 48 at the sides of the support bracket side arms, 28, 28 and concentrically with the pivots of the switch blades 24 and of the actuator lever 31. This bail member, as shown, is twisted at a central point 49 in its spanning portion, so as to engage with a slot cut in the extreme upper end of the actuator lever,—this construction permitting of ready disassembly of parts and also allowing of slight, radial movement to compensate for lack of absolute concentricity between the bail crank and actuator lever pivots. As will later appear, the bail crank 47 is ordinarily inclosed within a casing, and, accordingly, I have provided a radial control arm 51 for operating the same, disposed to swing outside of the casing and carrying the crank handle 52 at its end. In Fig. 6, two casing mounted check studs 53, 53 are shown as co-operating with a rearwardly extending portion 54 of the arm 51 directly to limit the latter's swinging movement, thus to render impossible any strain on the interior mechanism through abuse of the switch control arm.

Method of manually operating switch.

So much of the actuating mechanism as I have already described, in itself, constitutes an improved construction in quick-break, hand-operated knife switches because of its simplicity, ruggedness and novel mode of operation, which latter is as follows: Swinging the control arm 51 upwardly throws the switch blades 24 into engagement with the contact clips 21, which as commonly constructed are of spring copper or some other resilient conductive metal and adapted to spread slightly apart to accommodate the blades when seated therein. The squeezing tension of the clips 21 against the blades offers appreciable frictional resistance to their withdrawal, so that upon swinging the control arm 51 forwardly, this frictional resistance ordinarily is not overcome, until appreciable separation has occurred between the actuator lever 31 and the connecting bar 26. Such separation obviously increases the tension in the connecting spring 41, tending to pull the blades out of engagement with the clips, so that at some point in the forward and downward swing of the actuator lever 31 this tension will have become strong enough to overcome the retaining

friction and cause the blades quickly to snap away from the clips 21, again to assume their normal abutting position relative to the actuator lever 31. When this action occurs the blow of impact between the buffer structure 34 and the connecting bar bracket 37 is to a large extent absorbed by the spring-opposed yielding of the buffer structure 34 to its retracted position shown in Fig. 8. It should be particularly noted, that laws of inertia and of static friction make necessary a greater accumulation of tension in spring 41 to overcome the dead friction of clips 21 when the arm 51 is moved very slowly than when moved very quickly, bringing about the advantageous result that the slower it is attempted to open the switch, the quicker will be the actual contact-breaking movement of the switch blades, because of this increased tension in spring 41.

Timer controlled detent parts.

The foregoing description has disregarded the presence of certain detent and catch parts that are involved in the timer-controlled, automatic operation of my improved form of switch actuating mechanism and that will now be described. In Figs. 1, 2 and 4 the buffer structure 34 is shown as provided with two similar, downwardly extending portions at opposite sides of the adjacent bracket arms, 29, 29 and each formed as a catch 56 which is operatively positioned to engage with a double latch member 57 pivoted at 58 also on both sides of said bracket arms and urged by a spring 59 to its position shown in Fig. 2, where a connecting portion 61 of the double latch member acts as a stop against the front edges of the support bracket arms. The dot-dash lines in Fig. 2 show how in the before-mentioned, retracted position of buffer structure, the catch 56 is normally held out of position to engage with latch 57; and from the foregoing, it will have become apparent that this catch is always so inoperatively held while the switch blades 24 and actuator lever 31 swing in unison relatively positioned, as in Fig. 8. Accordingly, no interlocking of catch 56 and latch 57 can occur during ordinary, direct, hand-actuation of the switch such as heretofore has been described.

Other detent means, also, are provided for arresting the switch blades in their circuit-making position. The bracket fitting 37 on the connecting bar 26 carries a stationary pivot pin 62 for a latch dog 63. The forward, nose portion of this dog is normally held in an uppermost position, as shown in Figs. 2 and 5, by the light coiled spring 64 located in a hollow portion of the dog. This dog, in the form shown, is cheaply constructed by closely folding over a blank sheet of metal at the portion of the dog that appears sectioned in Fig. 5, and by

spreading the metal to form a hollow in the dog's pivoted portion therebelow, on each side of which hollow portion two stop-feet 66 of the dog extend downwardly to engage with a shelf 67 that is formed in the bent metal connecting bar fitting 37 for limiting the upward movement of the dog's nose portion. Figs. 1 and 5 show a detent lever 68 free to swing on a pivot pin 69 mounted in bracket ears 71 struck forwardly from the support plate 10, the forwardly extending arms of this lever carrying between their ends, a spherically shaped, detent block 72 having a central recess 73 cut obliquely therein as shown in Fig. 5. This detent block is so positioned through abutment of the lever 68 against a stop 74, as to fall directly in front of, and in position to engage with, the nose of dog 63 when the switch blades are nearly seated in their contact clips. Bearing on the upper, spherical surface of the block 72 is a presser foot 76, carried by the feeler lever 77 and vertically adjustable on the latter by means of the screws 78, 78. The feeler lever 77 is bent at its mounted portion so as to have bearing at two points on a pivot bolt 79 which near its head passes through, and is supported by, an overhanging bracket formation 81 struck out from the support plate 10, and also screws into the support plate 10. A light coiled spring 82 assists gravity in normally urging the swinging detent block 72 and presser foot 76, to their lower positions so that the former may be engaged by the nose of the latch dog 63 as clearly shown in Fig. 5. The nature of this engagement however is such, as will be apparent from inspection of Fig. 5, that the forward thrust of dog 63 on the detent block 72 acts in such angular relation relative to the pivot pin 69 of lever 68 as to urge the said block and lever upwardly about the pivot pin 69 to permit escapement of the dog. The proportional magnitude of the force component tending thus to thrust the block upwardly relative to the total pull exerted by spring on the connecting bar depends on the angle of engagement between the block 72 and the dog 63. It will be noted that the reactive thrust on the dog is in such direction relative to the latter's pivot 62 as to be positively opposed by the abutment of the dog's foot portion 66 against the bracket fitting 37. Downward yielding of the dog's nose portion, however, may always act to permit the dog to pass the detent block (whether or not the latter can yield upwardly) in the opposite relative direction of travel. I preferably arrange the angular relation of engagement between dog 63 and block 72 so that only a very small proportion of the total force of spring 41, tending to pull the dog forwardly past the block, is transferred into a component effective to urge the block up-

wardly, and, accordingly, by far the greater part of this force is borne as a direct pull upon the pivot pin 69. Even this small component of force however is, in effect, still further diminished through multiplication of leverage so that ultimately a very slight pressure applied downwardly at the upper, free end 83 of feeler lever 77 is operative positively to block the upward yielding tendency of the detent parts when the blades are put under the relatively heavy tension of spring 41 to cause their circuit-breaking action.

The timing mechanism.

Identically as in the structure of my co-pending application, hereinbefore referred to, it is the function of the simple timer mechanism employed to block and at a predetermined time to release the end 83 of feeler lever 77 to prevent or permit the above described yielding movement thereof at each forward escapement of dog 63 from detent block 72 as is necessary to permit circuit-breaking action of the switch. This timer mechanism is fully described in detail in my said co-pending application, and therefore it will suffice here to state that the immediately operative element thereof is a rotatable cam 84 mounted on a squared portion 85 of the main, timer-spindle, which latter has bearings in the frame of the escapement movement 14 and is constantly urged to rotate clockwise (as viewed in Fig. 1) by the band spring 86, to a stop-limited position as determined by engagement of the cam carried arm 87 with a frame mounted stud 88. All spring-caused, clockwise rotation of this cam and spindle, however, is retarded by the balance-wheel escapement movement above mentioned that is fully illustrated in the drawings but not here necessary to describe. The arrangement is such that at all times the timer cam 84 may be manually adjusted by turning the timer control-hand 89 in either direction to any desired rotative position,—the degree of energization of band spring 86 being always proportional to the amount of counter-clockwise, rotative displacement of the timer control hand 89 from its zero position (indicated by dot-dash lines in Fig. 1). In this figure, however, the control hand 89 is shown (in full lines) as set at the graduation "10" on an associated, casing-mounted dial 91, that is appropriately marked to indicate the time consumed in return of the pointer handle to its zero position from its different possible time settings. Also in Fig. 1, a notch 92 in cam 84 is shown as correspondingly displaced from a normal position indicated in dot-dash lines, in which latter position (corresponding to the zero position of the timer control hand) it registers with the end 83 of feeler lever 77 so

that the latter may enter this notch for permitting circuit-breaking movement of the switch blades.

Attention, however, is particularly called 5 to the improved construction my present invention provides for mounting and operating the timer cam 84. The hollow hub 93 of this cam contains a compression spring 94 retained by the spindle terminal nut 96, 10 this spring constantly urging the cam rearwardly to an axial position for operative alignment with the end of feeler lever 77. The novelly formed, one-piece, punched-metal control hand 89 for the timer, which 15 is retained on a squared terminal of hub 93 by the cap screw 97, is cheap to construct and is convenient to manipulate for turning the cam 84 to its desired operating setting, as well as for pulling the same axially for- 20 wardly as a means for instantly effecting release of the switch from control of the timer. Heretofore direct hand release of the switch for circuit-breaking action, after the timer has been set in operation, has ne- 25 cessitated rotatively returning the hand to its zero position,—removal of the cam from engagement with feeler arm through axial movement being, in this connection, an im- 30 proved and more convenient method of ef- fecting such release. The novel details of 35 my invention just described simplify and render more convenient to operate analogous parts as heretofore constructed in apparatus of this character.

35 *Mode of operation under timer control.*

When the timer is to be used for controlling automatic, circuit-breaking action of the switch blades (which action, as effected 40 directly by hand manipulation has hereinbefore been described) the operation is as follows. Either before, or after, the switch is closed, the timer control hand 89 may be turned counter-clockwise away from its nor- 45 mally idle zero position to the desired time setting. Upon release, it automatically begins its retarded, spring-driven, return to its zero position. The band spring 86 has been wound by this setting operation and 50 the cam 84 rotated so that its notch 92 is removed from position to permit yielding of feeler lever 77,—the periphery of said cam now positively preventing such yielding, until return of the notch 92 to its dot-dash 55 position in Fig. 1. The detent block 72 is thus locked in its lower position by the presser foot 76 and in such position will prevent passage of latch dog 63 when en- 60 countered by the nose thereof in opening movement of the switch blades 24. The actuator lever 31, however, when swung forwardly, to tension the spring 41, becomes automatically locked in its extreme outward and downward position (as shown in Figs.

1 and 2) through engagement of catch 56 65 with latch 57, these parts being co-operatively formed to pass smoothly into locking engagement. The switch is now set for timer-controlled, circuit-breaking action.

Although emergency means for manually 70 tripping the latch 57 to free catch 56 are provided in the bell-crank arm 98 that extends rearwardly and downwardly through a slot in the bottom of the casing box (as shown in Fig. 2), I will now point out a 75 novel and advantageous feature in automatic switch action resulting from the improved arrangement of parts that I have devised. Upon timer-determined circuit-breaking action of the switch blades, the hammer blow 80 of connecting bar 26 against the buffer structure 34, as before stated, is mostly absorbed by causing the latter to yield to its retracted position indicated by dot-dash lines in Fig. 2. It will be obvious, however, that such 85 yielding of the buffer structure results automatically in the disengagement of catch 56 from latch 57 so that the very locking means which having been maintaining tension in 90 spring 41 tending to cause circuit-breaking switch movement become unlocked by, and near the extreme end of, that movement. This automatic action eliminates the necessity for providing means manually to release the catch 56 each time before closing 95 the switch.

Since, however, the tension in spring 41 acts to effect no absolute movement of the blades (but only their movement relative to the actuator lever, which itself is pivoted 100 and free for movement except when locked by the catch 56) it follows that after such automatic unlocking of catch 56, as described above, the blades have no more tendency to continue in their direction of circuit-breaking movement than the actuator lever 31 (now also free for movement) has to fly up to meet the connecting bar 26,—except for such kinetic energy as is possessed by the connecting bar as a result of its initial mo- 105 mentum. From inspection of the relation of parts and consideration of the mechanical conditions involved, it will be apparent there may arise a distinct tendency of the actuator lever 31, and thereby of the switch blades 24, to rebound in the direction of their switch-closing, swinging movement unless some means counteracting such tendency is present. Obviously, I might provide a friction seating or the like that would catch and hold the switch blades in their extreme "off" position. But the necessary resistance ex- 110 ereted by such seating, and constituting its use, would then be encountered at each direct, hand controlling movement of the switch;—an undesirable feature, since a primary object of the present invention is to 115 provide a time switch whose normal oper- 120 125

ative characteristics are solely those of an ordinary, hand-operated knife switch.

Shock-absorbing buffer mechanism.

5 I will, therefore, point out in detail how the character of arrangement that I have devised, without employing additional elements for the purpose, positively counteracts all tendency of the blades to rebound, 10 and in addition constitutes a shock absorptive contrivance of such merit, that by actual test, although the tension in spring 41 and the blow of the circuit-breaking switch parts caused thereby are necessarily considerable, 15 yet the shock of that blow is so effectively damped, that when the entire structure sits upright, on end (as positioned in Fig. 2 and without fastening or support of any kind) no perceptible movement of the structure as a whole is caused by the abrupt and 20 powerful automatic switch action.

Referring to Fig. 2, it is apparent that tendency of the actuator lever 31 to rebound in a direction to close the switch must constitute a tendency of this lever to turn about its pivot 32. The effective magnitude of such turning tendency, (known to the mechanically skilled as a "turning moment") is, in part, determined by the distance from 30 the said pivot to the point of application of the acting force (in this case the reactive force of impact). More accurately, however, such turning moment is directly proportional to the perpendicular distance from 35 said pivot to the line of direction of the effective component of the applied force, such effective component, of course, being that part of the total applied force which acts in a direction tangential to the arc of movement of that point on the actuator to which it is applied. This is merely saying, that the magnitude of the tendency of the freely swingable parts to rebound is proportional to the effective leverage possessed by the 40 force of impact in respect to the pivot of the actuator lever. The smaller, therefore, such leverage can be made, the smaller will be the tendency of actuator lever 31 to rebound as a result of the hammer blow of 45 connecting bar 26 against the buffer structure 34, which blow, after full yielding moment of the buffer structure, must, of course, ultimately be transmitted to the actuator lever, since the buffer structure is wholly 50 carried thereby. Based upon considerations of these simple principles of mechanics, I have devised a shock absorbing arrangement composed of simple pivoted parts whose novel features may be availed of to advantage 55 in connection with buffer structures in general and regardless of the particular nature of the apparatus with which they are used. The novel principles referred to are broadly these: By pivotal, (or other) movable mounting of a yieldingly-positioned

buffer structure on a separately and eccentrically pivoted carrier member (required to be free to turn about its pivot), and by providing a stationary stop abutment, operatively independent of the said pivoted member, but positioned to be struck by the said buffer structure for ultimately checking the latter's yielding movement,—so relatively to arrange these parts that the force of the buffer-received blow (as ultimately transmitted to the freely swingable carrier member), shall react on said member in a line of direction that passes approximately through the pivot of said member, and that meets, therefore, substantially a "dead center" opposition and therefore sets up no tendency of the carrier member to turn about its pivot. The manner in which the particular embodiment herein concerned exemplifies this principle of arrangement and action in 85 buffer construction is next described.

It is clearly shown in Fig. 2 that the buffer structure 34 when struck by the connecting bar fitting 37 yields abruptly to its position indicated by dot-dash lines. But 90 here it is to be noted that before the forwardly bent portion 44 of the upper buffer structure reaches the edge of the actuator lever 31 (against which it is designed normally to abut as shown in Fig. 8), the 95 shoulder portion 99 of the buffer has encountered the top of latch lever 57. It is only for convenience of design in the particular structure concerned that the latch 57 serves thus as a positive independent stop 100 abutment for the buffer; as any stationary abutment correspondingly positioned would serve the same operative results. Obviously the force of the impact between buffer structure 34 and the latch 57 (or equivalent fixed stop) sets up a tendency of the buffer structure to rock to the left upon its shoulder portion 99 about the top of latch 57 as a fulcrum, this rocking tendency being transmitted to the pivot 33 of the buffer 110 as a pull almost radially in respect to the pivot 32 of the actuator lever. In other words, the force of impact, as ultimately transmitted to the actuator lever 31, acts in a line of direction passing through the lever pivot 32 and therefore sets up no appreciable turning moment in either direction of swing and therefore no tendency of the actuator lever 31 to rebound in a direction to close the switch, thus enabling this lever, 115 at the end of the automatic action, to be left unrestrained and entirely free for further movement. The switch blades 24, themselves cannot, of course, rebound because they are connected by the heavy spring 41 to the actuator lever. It should further be noted that did the nature of the apparatus so require the lever 31 could as well be left free for further-downward swinging movement and still, through the principle of buffer action 125 130

above described, serve the double office of carrying the buffer and of acting as the ultimate positive stop therefor when the latter yields to the blow of impact.

5 *The indicator mechanism.*

I will now refer to the casing parts, hereinbefore disregarded, and then describe the novel and simple means illustrated in Figs. 10 7, 8 and 9 for effecting a co-operative, safety interlocking action between my improved switch and its covering hood, to prevent accidents to the operator through thoughtless contact with a live switch or 15 fuses.

As Figs. 1 and 2 clearly show, these casing parts comprise principally a plain, rectangular, punched-metal box 101, the upper portion of which is covered by a compound 20 false cover comprised of a front plate 102 and a partition plate 103 in the rear thereof and spaced therefrom, which cover is secured by screws 104 to ears 105 formed at the 25 edges of the box. Between these spaced cover plates, as a convenient means for registering "on" and "off" positions of the switch, I may mount, as shown in Fig. 3, a swinging sign carrier 106 pivoted at 107 and normally held in an uppermost position by the spring 30 108, but depressible against the tension of this spring to a lower position wherein the carrier sign reading "On" registers in a window opening 109 in the front plate thereby to obscure another, stationary sign reading "Off" that is permanently imprinted on the front surface of the partition plate 103 to appear in said window when the "on" sign is absent therefrom. As operating connection between the carrier 106 and the 35 switch, I may provide the simple crank wire 111 that is conveniently mounted to swing in a bracket 112 formed by forwardly projecting portions of the partition plate 103. One arm of the crank wire 111 passes 40 rearwardly through a cut away 113 in the front plate to engage the carrier 106 while the other and longer arm is curved and extends downwardly to be actuated (in a manner clearly understood from Figs. 2 and 3), 45 by a portion of pivot pin 62 which extends beyond the bracket fitting 37 to the right. The crank wire 111 is preferably formed and positioned to be encountered for swinging the "On" sign to registering position in the 50 window 109 slightly before the switch blades 24 make contact with the slips 21 in the circuit-closing movement of the switch.

55 *The interlocking safety enclosure.*

60 Inclosing the sign-actuating crank wire 111, as well as the entire switch with its operating mechanism, is a forwardly bulging cover hood 114. This hood is hinged at rearwardly extending lower portions of its 65 side walls (that overlap the sides of casing

box 101) by pivot screws 116. Fig. 7 shows the hood 114, at its pivoted portion on the left of the casing, carrying fixed thereon a lateral plate cam 117 that normally falls in alignment with another rotatable cam 118 pivoted 70 directly above by means of the construction shown as sectioned in Fig. 1. In the side arm 28 of support bracket 27 is fixedly mounted a bearing bushing 119 through which extends a connecting shaft 121 that 75 is squared at each end of a central, round portion. The cam 118, before mentioned, is axially slidable on the outer squared portion 122 of this shaft but is normally maintained at an innermost position thereon by the compression spring 123 retained within a punched metal hub portion 124 of the cam 118 by a hub guide nut 126 mounted at an outer threaded extremity of the squared shaft portion. At its inner end the shaft 80 has riveted to its other and shorter squared portion the radially extending upright plate 127, to which latter is securely fastened a block 128 of insulating material, the opposite face of which is grooved to engage, and 85 swing with, the left switch blade 24, between its hinge clip 19 and contact clip 21. A retaining screw 129 holds the block and blade in positive engaging relation while permitting relative radial sliding movement 90 therebetween, if necessary, by means of the elongated slot 131 in block 128.

95 Figs. 7 and 8 clearly show the plate cams 117 and 118 as so formed that by engagement of a radial portion of either one there-of with a peripheral portion of the other, the co-operative action is such as positively to preclude closing of the switch except when the casing is closed and positively to preclude opening of the casing except when the switch is fully open. Such mode of operation, while effected by very simple means, provides a desirable form of safety construction that guards most effectively against 100 shock to the operator through careless contact with live switch parts by making it impossible for the operator to have access to the switch except when the latter is in its fully "off" position. The squared shaft 105 1121 and retaining spring construction are 110 provided, however, to permit convenient removal of the self-restoring cam 118 from axial alignment with cam 117 thus to throw the parts out of interlocking relation when for some designed purpose it is necessary 115 120 to close the switch with the casing open.

125 In addition to the automatically acting lock cams 117 and 118, Figs. 7, 8 and 9 show a convenient construction that may be compactly associated therewith for permanently preventing (by a common padlock 131) all access to the switch chamber (and in the form shown, also to the timer chamber) except by authorized persons. This construction comprises a hinge bracket 132 mounted 130

on the side of the casing box 101 to which bracket is pivoted the swinging lock bar 133, the latter being provided with a slot 134 adapted to engage a projecting tongue 136 formed on the hood cam. As the bar 133 swings to its locking position, shown in Figs. 7 and 8, wedging action between the left end of slot 134 and the left edge of tongue 136 forces and holds the switch covering hood tightly closed.

Automatic sign mechanism.

Attention is now directed to Figs. 10 to 18, inclusive, wherein, for the purpose of causing appropriate operating directions to appear at different times, there is shown an elaboration of the general type of indicator mechanism of Figs. 2 and 3, comprising a plurality of pivoted sheet metal sign carriers, of which the carrier 106' operates similarly to, and bears the same "On" sign, as the carrier 106 in said Fig. 3. But here the former carrier is arranged, by its up and down swinging movement to effect simultaneous up and down swinging movements of a second sign carrier 137 pivoted idly at 138 to the front plate 102 and normally positioned to fall diagonally across the carrier 106' in back thereof as shown in Figs. 10 and 11. Interposed between front carrier 106' and rear carrier 137 is a third carrier 139 that swings on the same pivot 138 with rear carrier 137. Reference may be had to the fragmentary sections shown in Figs. 12 to 15, inclusive, for better understanding the following description of the exact construction. In said figures, the three vertically aligned pairs of dot-dash lines by greatly exaggerating dimensions of thickness, represent in side elevation the closely adjacent planes in which the three sign carriers 106', 137 and 139, respectively, swing. Each of these carriers is stamped from thin sheet stock and is entirely flat except for certain overlapping ears formed co-operatively therewith, and in a co-planar relation thereto, the other carriers that is clearly indicated in the last mentioned figures. The ears 141 and 142, shown as sectioned respectively in Figs. 12 and 15, extend rearwardly from the front carrier 106' and overlap rear carrier 137, without interference with intermediate carrier 139, to guide the rear carrier 137 at its points of engagement by the front carrier through which it is actuated. In the downward swinging movement, this actuation occurs through cam action of the right hand edge of ear 141, where it is turned backwardly, with the upper convex edge 143 of a spur formation on rear carrier 137. In upward swinging movement the front carrier 106' swings the idler rear carrier 137 simultaneously upwardly through co-operative cam action between the upper edge of ear 142 (where

it is turned backwardly) with a lower convex edge 144 of the rear carrier. Figs. 13 and 14 show the only operating connection of the intermediate carrier 139, this connection comprising a curved tongue 146 bent sharply to the rear from intermediate carrier 139 and immediately upwardly after passing through a correspondingly curved slot 147 in the rear carrier 137. As clearly shown in Fig. 18, the tongue 146 at its lower portion is normally held downwardly against the lower edge of the slot 147 by a light wire spring 148, which latter at its free end is guided in a seat formed at the back of the rear carrier by said tongue, this spring being anchored at its opposite end in a rearwardly turned ear 149 formed from the rear carrier 137 as plainly shown in Fig. 14. Normally the spring 148 acts to hold rear carrier 137 and front carrier 106' in their aligning position shown in Fig. 10, but may bow resiliently to permit relative separating movement therebetween in one direction of swing, as hereinafter to be described. Fig. 10 shows a new element added to the switch-operating, bail-crank 47' that engages the actuator lever 31, this element being a rigid wiper tongue 151 secured, for convenience, to the under side of the said bail-crank and extending rearwardly therefrom at a point slightly to the left of its center. This tongue as viewed in Fig. 16, conforms to the curve of a circumferential arc relative to the pivot of bail-crank 47'. Fig. 10 also shows, in addition to the bracket-supported, carrier-operating, crank-wire 111 of Figs. 2 and 3, a similar crank-wire 152 pivotally carried by bracket extensions 153 similarly formed from the partition plate 103,—one arm of the latter crank-wire extending rearwardly to work under a forwardly projecting lug 154 on the intermediate carrier, and the other curved arm extending generally downwardly to be encountered by the above described wiper tongue 151. A stop clip 150 is carried by each of crank-wires 111 and 152 to limit their downward swing. The carriers 137 and 139 above described respectively bear a differently worded sign directing the operator how to manipulate the control agencies of the time switch, these signs in the lower position of their carriers being positioned to register back of a second window opening 155 near the right side of the front plate, best shown in Fig. 19. The function of this direction indicator mechanism is as follows.

Operation of the sign mechanism.

When looking at the front of the inclosed time-switch, the operator sees before him in the two front-plate windows, one of the different sign combinations appearing either in Fig. 10, Fig. 17 or Fig. 19. Assuming

that the switch is open, he is confronted with the sign "Off" in the left window informing him that the switch is open and by the sign "Swing arm up" in the right window, bearing a diagonal arrow as shown, which arrow in the assembled structure points directly to the switch control arm 51 at the right of the cover hood 114. The latter sign clearly directs him how to close the switch. It should be noted that the sign "Swing arm up" as is the case with the sign "Off" is stationary and carried by the partition plate. When the operating directions are followed and the control arm is swung up to close the switch, the visible signs are changed to those shown as registering in the two windows in Fig. 17. Such change of signs in the left window has been caused by the depression of carrier 106' against the tension of spring 108 exactly as in the construction of Figs. 2 and 3, the stationary "Swing arm up" sign in the right window at the same time having also been covered by downward swing of the rear carrier 137 as effected in a manner heretofore described.

In Fig. 17 it will be noted that the intermediate carrier 139 is still held in its uppermost position by the wiper-tongue 151 through the medium of crank-wire 152, and against the tension in spring 148 that now tends to swing the intermediate carrier 139 downwardly. Since the wiper tongue 151 engages crank-wire 152 for holding intermediate carrier 139 up, at substantially the same time crank-wire 111 is encountered by the pin 62 to depress the front and rear carriers 106' and 137, it follows that in ordinary, direct, hand actuation of the switch the intermediate carrier 139 and its sign "Turn hand back" never appears in the window 155. The operator in the position of parts in Fig. 17, reads "On" in the left window informing him that the switch is closed, and in the right window reads the operating directions "Swing arm down" informing him how to manipulate the control handle to open the switch. On again closing the switch it will be understood that the spring 108 restores all carriers to their upper position thus clearing the windows in the front plate of all movable signs.

The function of the sign worded "Turn hand back" will now be explained. It will be recalled that there is a possible third condition of the switch-operating mechanism in which the switch is tensioned for automatic, timer-governed actuation, and in which condition of the operating mechanism the switch control arm 51 is locked in its lower extreme position by catch 56 and the switch blades 24 are held in circuit making position against the switch-opening tension of spring 41, so that now a different mode of manipulation of the central agencies must be resorted to for opening

the switch. It is the function of the sign "Turn hand back," borne by the intermediate carrier 139, to inform the operator concerning this different mode of operation whenever such different mode of operation is necessary. In other words, only when the switch is tensioned and under control of the timer, the sign "Turn hand back" is caused to appear in window 155. Fig. 19 shows the switch blades 24 held in their "on" position by the timer controlled detent parts,—this closed condition of the switch remaining truly registered by the sign "On" in the left window of the front plate, but said figure also represents the switch control arm as depressed and the actuator lever 31 accordingly withdrawn and locked in position for tensioning the switch. Accompanying withdrawal of the tongue 151 on bail-crank 47' has released the crank-wire 152 and permitted the intermediate carrier 139, with its sign "Turn hand back" to drop in front of the "Swing arm down" sign under impulse of the wire spring 148. It will be noted that the latter sign also has an arrow but that this arrow points to the timer control hand 89 thus unmistakably indicating the control agency of the time-switch to which the sign refers, and plainly informing the operator (who presumably has just turned the timer control hand away from its zero position for putting the switch under timer control) that to open the switch he must return the timer control hand to zero. Obviously the latter mentioned sign might as appropriately be worded "Pull hand forward."

It will be appreciated that the wording of the signs as employed in the indicating mechanism described above is but arbitrary, and is intended merely to illustrate a novel operative principle applicable to indicating mechanisms in general,—the principal and obvious advantages of which resides in that greater simplicity and self-evidentness which results from the timely and automatic presentation of operating directions only in such part as is pertinent for instructing the operator how to manipulate the control agencies in the existing operative condition of the apparatus. The old and customary method for presenting operating directions in connection with apparatus requiring special and unfamiliar methods of manipulation has been to list such direction in their entirety on a name plate or some constantly exposed part of the structure, thus requiring the unskilled operator to study and become familiar with all of the operating directions before he can correctly and with convenience make any use of the apparatus concerned. It is believed that the provision of an arrangement designed to present successively only the pertinent parts of a complete set of operating directions is broadly novel and

that its practical advantages over the old method of listing operating directions in full are self-evident.

Modification of the interlocking enclosure.

I have hereinbefore mentioned the customary employment of fuses in inclosed switch construction and accordingly in Figs. 20 and 21 show how such fuses, as appearing at 160, can readily be incorporated within the lower part of the switch chamber of my improved time switch through lengthening of the closure parts. If, however, the hereinbefore described construction for hinging the switch covering hood 114 is to be preserved, such lengthening of the casing may require appreciable further separation of the pivots for cams 117 and 118, in Figs. 7 and 8. Since in some cases it might be inconvenient to compensate for such increase in pivot spacing by sufficiently extending the peripheral portions of said cams to maintain their direct interlocking engagement, I have shown in Figs. 22 to 25, inclusive, how I may interpose idler lock means mounted to operate between two equivalent cams 117' and 118' that are mounted to turn in unison with the cover hood and the switch blades, respectively, in the manner of cams 117 and 118 above mentioned. Such lock means, however, are preferably arranged in a way to retain the same simple and effective principles of interlocking action illustrated in Figs. 7 and 8. As disclosed herein, such interposed lock means constitute two pivoted idler plates 156 and 157, although a single member could for most purposes as well be substituted therefor. These idler plates lie flat against each other and are retained in contact, frictionally, if desired through pressure of a spring such as 158 under the head of screw stud 159 mounted on the side of the casing box 101. The inner plate 156 at its radial extremity has an outwardly projecting lug 161 against which an under concave edge of the outer plate 157 abuts. From the nature of their mounting it will be understood that these two plates yieldingly maintain any rotative position to which they are moved. An oblique edge 162 near the radial extremity of the outer plate is swingable to a position for engagement with a corresponding oblique edge 163 of the switch-blade-connected cam 118' and a similar oblique edge 164 of the inner plate adjacent the lug 161 may swing to a position for engagement with an oblique edge 165 of the hood-carried cam 117'. The nature of obliquity of the cam edges referred to above is obviously such in relation to the pivot point of cams and to that of the idler plates, that either cam is adapted to thrust its associated idler plate from the path of cam movement unless said plate is by some means held against turning. Each of Figs. 22, 24

and 25 shows the plates thus positively held in respectively different relative or absolute positions by a lock pin 166 carried on a lever 167 hinged at 168 and having for convenience of manipulation a handle knob 169. The lock pin 166 is adapted for insertion in either one of a pair of adjacent holes 171 through each of the idler plates and then into a registering hole 172 in the side of the casing box. Each pair of the lock pin receiving holes in each idler plate may respectively align, as they are shown in Figs. 22 and 24, or only two of the four holes may align as shown in Fig. 25, thus enabling the lock pin to secure the idler plates in any one of three different combinations of positions. The padlock 131 is accommodated by a hole in the fixed bracket tongue 173 mounted on the casing box 101 in a position to pass through a slot 174 in the lock carrying lever 167.

Operation of the modified interlocking enclosure.

In describing the operation of the safety and locking construction described above the lock-pin 166 will be considered as withdrawn, or positioned, as shown by dot-dash lines in Fig. 23. The idler plates 156 or 157 are now free to be shifted in unison at the urgency of either of cams 117' or 118' but only when the other of said cams is positioned as in Fig. 22. In Fig. 22 the switch is supposed to be open and the cover hood 114 is shown as closed. Although the inner idler plate 156 is shown in this figure as lying in the path of movement of the hood cam 117', it is obvious that movement of the latter cam in a clockwise direction (as occasioned by opening of the hood) thrusts said plate from its path and thereby the plate 157 into the path of the switch connected cam 118'. Such displacement of the idler plates, however, could not occur if the switch were in other than its "off" position, 110 for in such other position, the cam 118' would occupy some correspondingly displaced position as indicated by dot-dash lines in Fig. 22, wherein its peripheral portion positively blocks the idler plate against 115 yielding movement. Thus opening of the hood is positively prevented except when the switch occupies its full "off" position, as in the case of the two directly engaging cams of Figs. 7 and 8. On the other hand, 120 the insertion of lock pin 166 in its padlock-retained position as shown in Fig. 22, may itself permanently lock the hood alone closed. In Fig. 24 a similar condition of automatic locking operation is shown in respect to the 125 switch cam 118' which operation will be self-evident from an inspection of the drawings in view of the above description. Fig. 25, however, shows how, for locking the idler plates in separated position so that each 130

occupies a locking relation in respect to its associated cam, the same lock pin 166 may be employed in the same manner, by the same padlock, permanently to lock both the switch 5 and the cover hood 114 against movement, the former in its "off" position and the latter closed.

It will be understood that the idler plates 156 and 157 are shown as pivoted members 10 only for convenience of illustration. There are occasions where it might be preferable to construct them as sliding members such 15 equivalent construction involving no problems requiring invention in view of the basically 20 novel principles of operation clearly explained above and fully illustrated by the preferred embodiment herein disclosed. An operating finger knob as shown at 175 may also be provided as a convenient means for 25 pulling the idler plate 157 out of operative locking alignment with the cam 118' when desired. A construction permitting such disalignment of the locking parts would not, of course, be used were it desired to avail 30 of the permanent locking means which I have provided to prevent tampering with the switch by unauthorized persons.

Although, for the sake of simplicity I have illustrated the principal features of 35 my present invention as embodied in a time switch wherein the switch is designed to perform only one automatic action each time it is tensioned and established under control of the timer, it will be clear to those skilled in the art that many of the novel 40 principles characterizing the structure I have herein described may be utilized in the production of a time switch designed to effect a plurality of automatic actions when once established under control of the timer.

Since constructive illustration of such plural acting type of switch may add to a clear understanding of the principles involved in the present improvements, it has 45 been included herein. It will be readily apparent, as a demonstrative example relative to this matter that the simple addition of a spring 176, tending when energized to swing the actuator lever 31' in a direction to close 50 the switch, and of suitable detent connections 177, 178, whereby rotary movement of the timer cam 84 (or of an equivalent timer moved element 180) acts at a pre-determined time to trip the movable latch 57' for releasing catch 56' (assuming here, of course, that said catch is deprived of its provision 55 for being automatically disengaged by yielding of the buffer structure 34) would enable a structure substantially similar to 60 the one I have herein disclosed to effect a double throw of the switch, first to open the switch and then to close it again (or vice versa if desired) under automatic control of the simple timer employed. Notch 92 in 65 cam 84' will preferably be so positioned and

of such circumferential extent that lever 77 will be admitted to same from the time lever 77 has first been freed by notch 92 to cause the first switch escapement to and including the time latch 57' is tripped by pin 180 to 70 cause second switch escapement so that in normal position of the cam 84' when the timer movement has stopped running both detents 72 and 57' will be rendered inoperative to interfere with hand operated action 75 of the switch to the ends and advantages explained in the opening paragraph of this specification.

I have pointed out, at appropriate places in the foregoing, detailed description, certain features of my invention believed to be characterized by broadly novel principles both in construction and function; and in preface to the following claims I wish to state that the language thereof is by no 80 means directed explicitly to the precise embodiment of my invention hereinbefore described; such embodiment being understood to constitute merely an illustrative example of many possible other equivalent means for 85 seizing upon the underlying principles involved.

I claim as my invention:

1. A self-indicating, safety-inclosed, time switch embodying in combination; a switch 95 and mechanism for establishing tension tending to actuate the same; a timer, including detent means governed thereby for controlling tension-caused actuation of the switch; a closure for said switch and for 100 said timer; separate control handles exterior of said closure for separately operating said switch and said timer, and further arranged upon designed co-operative manipulation thereof to tension the switch for 105 automatic action under control of the timer; a door in said closure governing access to the switch; automatic interlocking mechanism operatively interposed between said door and the switch to lock the door closed when 110 the switch is closed whether independent of, or under control of the timer; and a movable signal carried by said closure and arranged to be differently positioned by movements of said switch and of its control handle thereby to indicate whether the switch 115 is under control of the timer while said door is locked closed.

2. A safety-inclosed switch and cut-out timer embodying in combination; a closure 120 for the switch and for the timer; a movable control handle outside the switch closure for operating the switch; connections between said handle and the switch whereby designed movement of the former tensions the 125 latter for automatic movement; operative connections between said timer and said switch whereby the latter when operatively adjusted acts to prevent said automatic switch movement for a predetermined lapse 130

of time; a manually actuatable pointer hand outside the switch closure for operatively adjusting the timer; a latch inside the switch closure for holding said control handle in a position to tension the switch when its automatic movement is prevented by the timer; tripping mechanism arranged to be actuated by said automatic switch movement to free the control handle from the latch; 10 and movable indicating signals operably related to the switch and to said control handle thereby to be differently positioned in respectively different operative positions of the switch, and still differently positioned 15 when the latter is tensioned by the control handle for automatic movement; together with means preventing access to said switch closure while the switch is closed and while tensioned for automatic movement under the 20 control of the timer.

3. Switch - actuating mechanism embodying, in combination with a movable circuit-governing switch member; a detent for releasably holding said member in a designed 25 operative position; a spring tending when operatively tensioned to impel said member away from its said position; a control lever movable to a position for operatively tensioning said spring; a catch adapted to lock 30 said control lever in its said position; and means operatively arranged between said member and said catch so that spring-caused movement of the member acts automatically to free said lever from said catch.

4. Switch - actuating mechanism embodying in combination with an oscillatory circuit-governing switch member; an oscillatory control lever mounted to swing with, and positively to impel said member in one 40 direction of its oscillation, and further arranged for swinging displacement from a normal position relative to said member in the opposite direction of oscillation; resili- 45 ent connection between said control lever and said member whereby said swinging displacement of the former tensions the latter for follow-up movement relative thereto; a detent for releasably holding said member to prevent its said follow-up movement; a catch adapted to lock said control lever in a designed position displaced from said member to tension the latter for automatic follow-up movement; and means operatively arranged between said member and 50 said catch so that said follow-up movement of the member operates to free said control lever from said catch.

5. Switch - actuating mechanism embodying in combination with an oscillatory circuit-governing switch member; an oscillatory control lever mounted to swing with, and positively to impel, said member in one direction of its oscillation, and further arranged for swinging displacement from a

normal position relative to said member in 65 the opposite direction of oscillation; resili- 70 ent connection between said control lever and said member whereby said swinging displacement of the former tensions the latter for follow-up movement relative thereto; a detent for releasably holding said member to prevent its said follow-up movement; a catch adapted to lock said control lever in a designed position displaced from said member to tension the latter for automatic 75 follow-up movement; and means operatively arranged between said member, said lever, and said catch, so that the latter is rendered inoperative to lock said control lever when said lever occupies its said normal position 80 relative to said member.

6. Switch - actuating mechanism embodying in combination with an oscillatory circuit-governing switch member; an oscillatory control lever mounted to swing with, and positively to impel, said member in one direction of its oscillation, and further arranged for swinging displacement from a normal position relative to said member in 85 the opposite direction of oscillation; resili- 90 ent connection between said control lever and said member whereby said swinging displacement of the former tensions the latter for follow-up movement relative thereto; a detent for releasably holding said member to prevent its said follow-up movement; a movable catch carried by said control lever and adapted to lock the latter in a designed position for tensioning said member for automatic movement, said catch being operably related to said member and thereby retracted and held in a position inoperative to lock said lever when the latter occupies its said normal position relative to 95 said member.

7. Switch - actuating mechanism embodying, in combination with a movable circuit-governing switch member; a detent for releasably holding said member in a designed 100 operative position; a spring tending when operatively tensioned to impel said member away from its said position; a buffer resili- 105 ently urged to a projecting position in the path of the spring-impelled member, thereby to absorb the blow of the latter by yielding to a retracted position; a control lever movable to a position for operatively tensioning said spring; a catch adapted to hold said lever in its said position; and operative connection arranged between said buffer and said catch so that the latter is rendered inoperative to hold said lever when the buffer occupies its said retracted position.

8. Switch-actuating mechanism embodying in combination with a movable circuit-governing switch member; an oscillatory control lever mounted to swing with and positively to impel said member in one direc- 125

- tion of its oscillation, and further arranged for swinging displacement from a normal position relative to said member in the opposite direction of oscillation; resilient connection between said control lever and said member whereby said swinging displacement of the former tensions the latter for follow-up movement relative thereto; a movable buffer for arresting the said follow-up movement of said member,—said buffer being carried by said control lever and resiliently positioned thereon to receive the thrust of said member when said control lever and member occupy their normal relative position, thereby to yield to a relatively retracted position: a detent for releasably holding said member to prevent its said follow-up movement relative to said lever; and a catch adapted to hold said lever in a position adapted to tension said member for automatic movement;—said catch being operably related to said buffer thereby to be rendered inoperative to lock said lever when the buffer occupies its said retracted position.
- 25 9. Switch-actuating mechanism embodying, in combination with an oscillatory circuit, governing switch member; an oscillatory control lever mounted to swing with and positively to impel said member in one direction of oscillation, and further arranged for swinging displacement from a normal position relative to said member in the opposite direction of oscillation; resilient connection between said control lever and said member whereby said swinging displacement of the control lever tensions the member for follow-up movement relative thereto; a detent for releasably holding said member to prevent its said follow-up movement; a catch for locking said control lever in a designed position operatively to tension said member; and a movable buffer structure pivotally mounted on said control lever and carrying said catch,—the said structure being resiliently positioned to be engaged by said member when the control lever occupies its said normal position relative thereto, and thereby caused to yield into a relatively retracted position wherein said catch is inoperative to lock said control lever.
- 10 10. In a time switch, in combination; a circuit-governing switch member pivoted for swinging movement; a rotatable timer element mounted on the same side of a common frame with said switch member; and detent mechanism co-operatively interposed in the space between said member and said element, the parts of said mechanism being normally urged into a position to free said timer element and to intercept said switch member; and the said parts being further arranged to yield against the pressure of said switch member to permit the escapement of same except when pre-
- vented from so yielding by engagement with the said timer element.
11. In timing mechanism that includes as its effectively operative element a spindle-carried cam designed normally to control a detent by rotative movement, a quick-release construction constituting the mounting of said cam to be axially slidable upon its said spindle between a position for alignment and a position for disalignment with its controlled detent,—said construction also including a cam-restoring spring arranged normally to urge said cam to the former of its said positions.
12. The construction of a time-indicating control hand for operating a rotatable timer cam, wherein said hand is formed from a strip of sheet metal having a relatively back-standing central portion for mounting the hand and having back-standing terminal portions, shaped in effect as the head and tail of a pointer arrow,—the portions of said strip of sheet metal connecting said central and terminal portions being formed as similar and relatively outstanding loops disposed in diametrical alignment, to provide a convenient finger grasp both for turning the timer cam and for sliding the same axially on its pivot.
13. In a multi-blade electric knife-switch including an insulating support panel and an insulating bar connecting the free ends of the switch blades, a protective construction for the mounting of actuating mechanism in operating relation to the switch blade connecting bar, wherein the insulating support panel for said switch is formed with two parallelly disposed fins extending perpendicularly to said panel between two of the switch blades and sufficiently spaced apart to accommodate therebetween the said actuating mechanism;—the outstanding edges of said fins being shaped to conform closely to the arc of travel of the switch blade connecting bar so as to afford complete separation between said actuating mechanism and said switch blades.
14. In combination; two elements normally held in abutting engagement by a connecting spring; two detents respectively positioned to retain each of the elements when they are relatively separated against the action of said spring; means to trip one of said detents to free the element held thereby for spring-caused return to abutting engagement with the other element; and means whereby the spring caused return of the element thus freed operates automatically to free the other element from the other detent.
15. In combination with an electric switch contact and timing mechanism for controlling automatic action thereof, an indicator conditionable by action of the switch contact to indicate different operative positions

of the latter, and means indicating whether said contact is under control of said timing mechanism.

16. In combination with an electric switch contact and timing mechanism conditionable to control automatic action of said contact, a movable signal actuated by movement of said contact to indicate the operative position of said contact and supplemental means co-operating with said signal to indicate whether said timing mechanism is operatively conditioned to control said contact.

17. In combination, an electric switch contact, a handle to operate said contact, timing mechanism, means to tension said contact for automatic action under control of said timing mechanism, a signal to indicate circuit controlling position of said contact and means indicating whether said contact is tensioned and under control of said timing mechanism.

18. In combination, an electric switch contact, a handle to operate said contact, timing mechanism, means to tension said contact for automatic action under control of said timing mechanism, a signal movable with said contact and an indicator movable relative to said signal to indicate whether said contact is tensioned and under control of said timing mechanism.

19. In combination, an electric switch contact, a handle to operate said contact, timing mechanism, means to tension said contact for automatic action under control of said timing mechanism, a signal actuated by movement of said contact and an indicator actuated by movement of said handle, said signal and indicator being established in respectively different relative positions when said contact is conditioned to be operated by said handle and when said contact is tensioned under control of said timing mechanism.

20. In combination with casing concealed time switch mechanism including a switch contact and an actuator therefor adapted for movement in unison and also for relative movement, means to indicate the operative condition of said mechanism, comprising a plurality of movable signals each adapted to become in part visible exterior of said casing; and operating connections between said contact, actuator and signals arranged upon different positioning of said contact and actuator in unison to cause re-

spectively different positioning of said signals and arranged upon relative movement of said contact and actuator to cause a still different positioning of said signals, thereby to distinguish visibly exterior of said casing between said relative movement of said contact and handle and said movements thereof in unison.

21. In combination with a time switch establishable in "on", "off" and "cocked" conditions by respectively different manipulation of its operating controls, the combination of differently worded inscriptions comprising respectively different directions for manipulating said operating controls said inscriptions being in part rendered visible at designed times; and indicator parts operated by said controls to conceal and expose respectively different parts of said inscriptions at any given time, whereby in each of said conditions of said time switch there is rendered visible such part of the said inscription as directs how next to manipulate the controls further to operate the time switch.

22. In a casing inclosed time switch the combination with two windows in said casing, of co-operating movable signs arranged to be automatically actuated by the time switch mechanism and thereby caused to appear in said windows in relation determined by condition of said mechanism, the wording of the signs that appear in one of said windows comprising an indication of the condition of the switch, and the wording of the signs that appear in the other window comprising directions for operating the switch.

23. In a time switch having as separate control elements a timer operating handle and a switch operating handle designed to be operated in particular sequence, the combination of a system of indicating signs arranged to be differently positioned and rendered separately visible by movements of said two handles, each of said signs bearing respectively different wording adapted to instruct how further to manipulate said handles.

Signed at Boston, Massachusetts, this 7th day of May, 1918.
